Primary Examiner — Jonathan J Han(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a top view thereof;

FIG. 4 is an opposite side view thereof; and,

FIG. 5 is an opposite side front perspective view thereof. The broken line immediately adjacent to the internal perimeter of the shaded area on the side panel element defines a bound of the claimed design and forms no part thereof. The broken lines depicting the remainder of the shoe form no part of the claimed design.
